UNITED STATES PATENT OFFICE.

FRANK ERNEST WILSON, OF LONDON, ENGLAND.

AUTOMOBILE-LIGHTING APPARATUS.

1,248,968.

Specification of Letters Patent.

Patented Dec. 4, 1917.

Application filed November 28, 1914. Serial No. 874,538.

To all whom it may concern:

Be it known that FRANK ERNEST WILSON, a subject of the King of Great Britain and Ireland, residing at 17 Seaton street, Euston road, London, N. W., England, has invented certain new and useful Improvements in Automobile-Lighting Apparatus, of which the following is a specification.

This invention for improvements in apparatus for use in connection with electric lighting systems on automobiles relates to apparatus for controlling the various lamps such as head lamps, side lamps, tail lamps and the like and has for its object firstly a compact apparatus comprising switches, meters and other suitable devices which shall be readily applicable to the dashboard and secondly an improved junction box facilitating the connection of the control apparatus to the external circuits. This apparatus is designed for use in connection with electrical installations which are supplied with current from a secondary battery working in conjunction with a generator.

The apparatus constructed according to the present invention consists essentially of a combined switch and meter box which is permanently connected by a length of flexible cable preferably armored to a junction box in which the electrical connections with the external circuits are made. The switch and meter box is adapted to be mounted on the dashboard of the car and comprises a set of switch levers mounted on a common shaft within the box and arranged to control the various external circuits and a combined voltmeter and ammeter. The meter is provided with a translucent dial and a low voltage lamp connected in series with the tail lamp is mounted behind the dial to illuminate the same and serve as an indicator as to the condition of the tail lamp.

One preferred form of construction is shown in the accompanying sheet of illustrative drawings in which:

Figure 1 is a front view of the apparatus and

Fig. 2 is a side sectional elevation.

As seen the switches *a* are assembled on a common spindle and mounted in a casing *b* of metal or other suitable material in such a manner that the switch handles project through the front of the casing *b*. A combined ammeter and voltmeter *c* controlled

by one of the said switches *a*¹ is let into the sloped front of the upper part of the casing and is illuminated from within by a small lamp *d* arranged in series with the tail lamp of the car to act as an indicator as to the condition of the said tail lamp.

Referring to the drawings it will be seen that the switches *a* consist of sectors bearing radial handles and are mounted on a common spindle *h* near the front of the casing, so that a portion of each sector together with said handles project through suitable apertures in the casing. These switches are further preferably constructed, so that they are capable of a certain locking action, so that when moved to either extreme of the apertures in the casing, it will be well nigh impossible for them to be swung out of said position, due to the jarring of the car. Each disk is provided within the casing with a knife blade or other suitable contact *l* adapted when the switch handle is in one extreme position to engage and electrically connect pairs of contact blades *m* mounted on a plate *n* of insulating material.

One of the switches *a*¹ which controls the dynamo is provided with two pairs of contact blades *m*, *m*¹ to constitute a two way switch for use in connection with the combined ammeter and voltmeter *c*. If desired another switch may be arranged in connection with the magneto in order to control the ignition of the engine.

The meter *c* being provided with a translucent dial the lamp *d* connected in series with the tail lamp on the vehicle serves to illuminate the dial and at the same time acts as a check on the tail lamp. A connector socket *o* of the bayonet or other suitable form is also provided on the casing for the attachment of an inspection lamp or other fitting.

When desired a cigar lighter of any approved form may be detachably mounted on the side of or within the casing and connected to the source of supply by a flexible cord winding on a spring drum inclosed in the casing.

The electrical connection between the control apparatus and the junction box *e* is permanent and consists of an armored cable which is secured to the casings of both apparatus. The junction box is formed of two half sections secured together by screws with

the removable terminal board *g* arranged between. The terminal board *g* is held in place by ribs *e* on the box sections which engage grooves in the board and is provided with any approved form of terminal screws for the connection of the leads from the lamps, battery, generator and the like. Preferably these terminals are arranged substantially in a circle around the board, a 10 large terminal being provided at the center for the assembly of the common wires.

With the above arrangements the wiring of an automobile is greatly simplified as after the control apparatus and junction 15 box have been attached to the dash-board and chassis respectively the circuit leads have only to be connected to the terminals in the junction box. In order to insure these connections being made correctly the 20 terminals are numbered and an explanatory diagram may be provided.

Furthermore, the above apparatus is simple and cheap of manufacture and at the same time occupies but small space on the 25 dash-board.

What I claim and desire to secure by Letters Patent is:—

A device of the class described comprising a casing provided with an opening through one of the side walls and an opening below 30 the first-named opening, a meter positioned within the first-named opening, said meter being provided with a translucent dial, a lamp arranged within the casing and behind said dial adapted to illuminate said 35 dial, a second lamp, the first lamp being arranged in series with the second lamp, whereby if the latter lamp, at any time fails to light, the first-named lamp will not be supplied with current and will consequently fail to 40 light whereby it will immediately become apparent to the operator that the second lamp is not lighted.

In testimony whereof I have affixed my signature, in presence of two witnesses.

FRANK ERNEST WILSON.
